United States Patent Office

Des. 211,888
Patented Aug. 6, 1968

211,888

SOAP HOLDER

John C. Hall and Gunter E. Milow, Los Angeles, Calif.,
assignors to Productline Incorporated, a corporation of
California

Filed Sept. 21, 1967, Ser. No. 8,677

Term of patent 14 years

(Cl. D33—24)

FIG. 1

FIG. 2

FIG. 3

FIG. 4

FIG. 5

FIG. 6

FIG. 7

FIG. 8

FIG. 9

FIG. 10

FIG. 11

FIG. 12

FIG. 13

FIG. 14

FIG. 15

FIGURE 1 is a perspective view of a soap holder showing our new design;

FIGURE 2 is a side elevational view thereof;

FIGURE 3 is a top plan view thereof;

FIGURE 4 is a bottom plan view thereof;

FIGURE 5 is a side elevational view of a modified form of the soap holder shown in FIGURE 1;

FIGURE 6 is another side elevational view taken from a position 90 degrees to that of FIGURE 5;

FIGURE 7 is a top plan view of FIGURE 5;

FIGURE 8 is a bottom plan view of FIGURE 5;

FIGURE 9 is a side elevational view of a second modified form of the soap holder shown in FIGURE 1;

FIGURE 10 is a top plan view of FIGURE 9;

FIGURE 11 is a bottom plan view of FIGURE 9;

FIGURE 12 is a side elevational view of a third modified form of the soap holder shown in FIGURE 1;

FIGURE 13 is another side elevational view taken from a position 90 degrees to that of FIGURE 12;

FIGURE 14 is a top plan view of FIGURE 12; and

FIGURE 15 is a bottom plan view of FIGURE 12.

We claim:

The ornamental design for a soap holder, substantially as shown.
